Primary Examiner — Brian N Vinson(74) *Attorney, Agent, or Firm* — Leanne Taveggia Farrell; Westman, Champlin & Koehler, P.A.(57) **CLAIM**

The ornamental design for a lamp, as shown and described.

DESCRIPTION

FIG. 1 is a perspective view of a first embodiment of a lamp showing our new design;

FIG. 2 is a front view thereof, the back view being a mirror image;

FIG. 3 is a right side view thereof, the left side view being a mirror image;

FIG. 4 is a top view thereof;

FIG. 5 is a bottom view thereof;

FIG. 6 is a perspective view of a second embodiment of the lamp;

FIG. 7 is a front view of FIG. 6, the back view being a mirror image;

FIG. 8 is a right side view of FIG. 6, the left side view being a mirror image;

FIG. 9 is a top view of FIG. 6; and,

FIG. 10 is a bottom view of FIG. 6.

The broken lines illustrate portions of the lamp and form no part of the claimed design.

1 Claim, 8 Drawing Sheets(56)
